US0D1075420S

(12) **United States Design Patent** (10) **Patent No.:** **US D1,075,420 S**
(45) **Date of Patent:** **** May 20, 2025**

(54) **TRAY FOR FOOD AND DRINK**

(71) Applicant: **Essentially Engineered, LLC**,
Cheyenne, WY (US)

(72) Inventor: **Jacob Lovasz**, Arvada, CO (US)

(73) Assignee: **ESSENTIALLY ENGINEERED, LLC**,
Cheyenne, WY (US)

(**) Term: **15 Years**

(21) Appl. No.: **29/898,253**

(22) Filed: **Jul. 25, 2023**

(51) LOC (15) Cl. **07-01**

(52) U.S. Cl.

USPC **D7/553.1**

(58) **Field of Classification Search**

USPC D12/423, 424, 421, 192, 400, 425;
D7/553, 396.4, 501, 505, 538, 540,

(57) **CLAIM**

The ornamental design for a tray for food and drink as shown and described.

DESCRIPTION

FIG. 1 is a perspective view of one embodiment of my new design;

FIG. 2 is a front view thereof;

FIG. 3 is a back view thereof;

FIG. 4 is a right side view thereof;

FIG. 5 is a left side view thereof;

FIG. 6 is a top side view thereof;

FIG. 7 is a bottom view thereof;

FIG. 8 is a perspective view of another embodiment of my new design;

FIG. 9 is a front view thereof;

FIG. 10 is a back view thereof;

FIG. 11 is a right side view thereof;

FIG. 12 is a left side view thereof;

FIG. 13 is a top side view thereof; and,

FIG. 14 is a bottom view thereof.

The broken lines in the drawings depict portions of the tray for food and drink that form no part of the claimed design.

1 Claim, 14 Drawing Sheets
